UNITED STATES PATENT OFFICE.

JAMES SIMPSON, OF LINDEN, NEW JERSEY, ASSIGNOR TO STANDARD OIL DEVELOPMENT COMPANY, A CORPORATION OF DELAWARE.

PREPARING HYDROCARBON PRODUCTS.

No Drawing.

Application filed January 30, 1924. Serial No. 689,590.

This invention relates to the preparation of petroleum distillates, and more particularly finishing light products.

Various undesirable compounds occur in 5 petroleums of different sources and impart in some cases detrimental characteristics to the products. Certain naphthas, for instance, contain organic sulfur compounds of more or less malodorous character and are "sour," 10 according to refiners' terminology. Other naphthas, for instance, may not be sour, but may exercise a corrosive action on copper, due to presence of sulfur in combinable form.

In accordance with the present invention 15 petroleum distillates with objectionable constituents, as aforementioned, can be advantageously and simply brought to a satisfactory condition.

The practice of the invention will be illustrated by an example which sets forth the principle involved: A cracked naphtha distillate, not treated with sulfuric acid, which contained constituents causing it to be "sour," 20 was treated with about 1% of a sodium plumbite solution or "doctor" solution made by dissolving about 1 lb. of litharge in 3 gals. of 15° Bé. aqueous caustic soda solution. By sodium plumbite or doctor solution I mean any of the solutions of lead oxide in caustic 25 alkali that are suitable for use in treating hydrocarbon oils. After thorough agitation, settling was allowed to occur and the doctor solution was drawn off below. The naphtha was then "sweet." This used doctor solution 30 was now in turn mixed in the proportion of about 5% with a naphtha containing corrosive sulfur, and after thorough agitation, settling was allowed to occur and the doctor solution was drawn off below. This naphtha 35 was then free from corrosive action.

In general usage it will be understood that the proportions of treating agent may be varied in accordance with the requirements of particular distillates to be treated.

40 I am, at present, unable to state just what the ultimate mechanism of the action is, and without committing myself definitely to any theory, merely suggest that the organic sul-

fur compound in the sour naphtha appears to react with the lead-soda compound of the 50 doctor solution to form an unstable compound with which the sulfur of corrosive naphtha in turn can readily combine. It is well understood in the art that such sulfur cannot ordinarily be removed by treatment 55 with the usual doctor solution.

It is important that the sour distillate or sour cracked distillate should not be treated with sulfuric acid before receiving the doctor solution treatment; and it is desirable that the 60 doctor solution which has been used on the sour distillate should be used within a few days for treating the corrosive distillate, since the active compound is unstable, and on standing gradually spontaneously decomposes and the solution is then inert. 65

While I have described my invention by reference to certain specific details, it will be understood that this is illustrative, and that changes can be made which come within the 70 spirit and scope of the invention.

What I claim is:

1. The process of preparing petroleum distillates, which comprises subjecting a sour naphtha distillate to the action of a sodium 75 plumbite solution, separating the said solution, and then subjecting a naphtha distillate containing corrosive sulfur to the action of the same solution.

2. The process of preparing petroleum distillates, which comprises subjecting a naphtha distillate, containing sulfur in corrosive form to the action of a sodium plumbite solution previously used to treat a sour cracked naphtha. 80

3. The process of preparing petroleum distillates, which comprises subjecting a distillate containing sulfur in corrosive form to the action of a sodium plumbite solution which has been used to treat a sour distillate. 85

4. The process of preparing a non-corrosive petroleum distillate, which comprises treating a corrosive distillate with a sodium plumbite solution containing constituents of a sour petroleum oil. 90

JAMES SIMPSON.
